EXERCISING DEVICE

Duane E. Mitchell, Shandon Road, Paso Robles, Calif.

Filed June 12, 1964, Ser. No. 80,377

Term of patent 14 years

(Cl. D34—5)

FIG. 1 is a perspective view of an exercising device showing my new design;

FIG. 2 is an end elevational view; and

FIG. 3 is a side elevational view thereof.

I claim:

The ornamental design for an exercising device, substantially as shown.
